(57) **CLAIM**

The ornamental design for a jewelry bead, as shown and described.

DESCRIPTION

The patent or application file contains at least one drawing executed in color. Copies of this patent with color drawings will be provided by the Office upon request and payment of the necessary fee.

FIG. 1 is a front view of the first embodiment of a jewelry bead showing my new design, the rear view being a mirror image thereof;

FIG. 2 is a front view of the second embodiment of a jewelry bead, the rear view being a mirror image thereof;

FIG. 3 is a perspective view of the first embodiment of the jewelry bead of FIG. 1;

FIG. 4 is a perspective view of the second embodiment of the jewelry bead of FIG. 2;

FIG. 5 is a side view of the first embodiment of the jewelry bead of FIG. 1, the opposite side view being a mirror image thereof;

FIG. 6 is a side view of the second embodiment of the jewelry bead of FIG. 2, the opposite side view being a mirror image thereof;

FIG. 7 is a top view of the first embodiment of the jewelry bead of FIG. 1; and,

FIG. 8 is a top view of the second embodiment of the jewelry bead of FIG. 2.

1 Claim, 8 Drawing Sheets
